(57) **CLAIM**

The ornamental design for a lazy susan, as shown and described.

DESCRIPTION

FIG. 1 is a perspective view of a first embodiment of a lazy susan showing my new design;

FIG. 2 is a perspective exploded view of the lazy susan;

FIG. 3 is another perspective view of the lazy susan;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is bottom plan view thereof;

FIG. 10 is a perspective view of a second embodiment of a lazy susan;

FIG. 11 is a perspective exploded view of the lazy susan;

FIG. 12 is another perspective view of the lazy susan;

FIG. 13 is a front view thereof;

FIG. 14 is rear view thereof;

FIG. 15 is a left side view thereof;

FIG. 16 is a right side view thereof;

FIG. 17 is a top plan view thereof; and,

FIG. 18 is a bottom plan view thereof.

The broken lines show portions of the lazy susan that form no part of the claimed design.

1 Claim, 18 Drawing Sheets
